STAPLING DEVICE

Charles I. Tager and Hans C. Stockel, Chicago,
Ill., assignors to American Die & Tool Corpora-
tion, Chicago, Ill., a corporation of Illinois

Application August 20, 1940, Serial No. 353,434

12 Claims. (Cl. 1-3)

This invention relates to a stapling device, and more particularly to improvements in a small stapler adapted for office use.

We contemplate a stapler of the type which may be used either in permanent stapling or in temporary stapling and accordingly we have provided our new device with means making this possible in a well known manner. Further, we have provided our new and improved stapler with means whereby the stapling head may be swung away from the base and be used as a tacking device without deformation of the staples.

The primary object of our invention is to provide a novel and improved stapling device of exceedingly simple construction and positive operation.

An object, collateral with the above, is the provision of novel methods for the formation of vital parts of our new and improved stapling device.

Still a further object of the present invention is to provide a stapler having novel staple magazine and associated parts.

Further, an object of this invention is to provide novel plunger guide means, novel staple ejection means, and novel plunger means for our new and improved stapling device.

Other objects of the invention are to provide a novel spring and plunger mechanism for forcing the staples of our new device into ejection position; novel means for concealing the magazine and associated mechanism; novel means for adding compression to the already compressed spring of the magazine mechanism of our new and improved stapling device.

Still further objects of the present invention lie in the provision of a novel ejection plunger positioning mechanism, novel housing for our stapling device; and novel cover means for the housing of our stapling device.

A further object of the present invention is to provide a stapling device of the character described of extreme simplicity so that same may be adapted for low cost production in large quantities without the sacrifice of any constructional and operational advantages.

With the foregoing and other objects in view which will appear as the description proceeds, the invention consists of certain novel features of construction, arrangement and combination of parts hereinafter fully described, illustrated in the accompanying drawings, and particularly pointed out in the appended claims, it being understood that various changes in the form, proportion, size and minor details of the structure

may be made without departing from the spirit or sacrificing any of the advantages of the invention.

For the purpose of facilitating an understanding of our invention, we have illustrated in the accompanying drawings a preferred embodiment thereof, from an inspection of which, when considered in connection with the following description, our invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a side elevational view of a stapling device embodying our new invention.

Fig. 2 is a median sectional view of our new and improved stapling device taken generally along the line 2-2 of Fig. 3 as indicated.

Fig. 3 is a sectional view taken through the housing of our new and improved stapling device as indicated by the line 3-3 of Fig. 2.

Fig. 4 is a plan view of the sheet metal blank from which the housing of our new and improved stapling device is formed.

Fig. 5 is a side elevational view of the rear end of our new and improved stapling device with portions thereof in section to show the operation of portions of our device.

Fig. 6 is a sectional view taken through the staple plunger of our new device along the line 6-6 of Fig. 2 in the manner indicated.

Fig. 7 is a bottom sectional view of our device taken generally along the line 7-7 of Fig. 2 and in the direction of the arrows, being in effect a bottom plan view of the device with the rubber base member removed.

Fig. 8 is a bottom perspective view of the plunger and depressing member of our new device removed therefrom.

Fig. 9 is a sectional view of our new and improved stapling device taken generally along the line 9-9 of Fig. 2 in the general direction indicated.

Fig. 10 is a fragmentary bottom plan view of the forward portion of the staple driving part.

Fig. 11 is a vertical sectional view taken along line 11-11 of Fig. 2 looking towards the front end of the device.

Generally, the invention lies in a novel and ingenious method of making our device and in the novel and improved combinations of features resulting in part from the method. As inferred

by the statement of objects above, one of the primary purposes of this invention is to reduce the cost of labor, materials and overhead in the mass production of a stapling device of this character, without detracting from its sturdiness, efficiency and appearance.

The invention contemplates a base, generally designated by the reference character 10, and preferably formed of sheet metal, provided with a pair of upwardly struck ears 11 upon which is pivotally mounted the staple driving head 12 by means of the screw or pin member 13. The pivotal mounting is shown in the drawings as screw and nut fastening means.

The base member 10 is provided rearwardly thereof with a bifurcation 14 to enable the head 12 to swing in an arc of 180° if it is desired to use the head without the base, as shown by the broken lines of Fig. 1. A soft rubber or the like protecting member 15 is provided to prevent the base 10 from scratching furniture upon which same is placed.

The base is provided with an anvil 16 pivoted by means of a rivet or the like 17 to a depression 18 formed therefor in said base. Said anvil 16 is circular so that it may be moved to its various positions with respect to the ejected staple which will come from the staple-driving head 12 as hereinafter described. Said anvil has an arm-like member 18 attached thereto and extending through an arcuate slotted opening 19 in the surface of the base member 10 whereby the anvil may be moved to either of two positions as defined by the limits of said slotted opening 19. In one position, the arms of the staple, which is of conventional inverted U-shaped form prior to deformation, are deformed inwardly in a well known manner to produce a so-called permanent staple; and in another position, the arms are deformed outwardly in producing a so-called temporary staple. The so-called permanent staple opening in the anvil is not shown in the drawings, but is conventional and well known in the art, and forms no part of the invention. Likewise, the openings 20 in the anvil which aid in the formation of a temporary staple, are shown in Fig. 3, but form no part of the present invention.

The rubber member 15 which is disposed upon the base 10 for preventing scratching of furniture or the like upon which the stapling device may be disposed, is provided with a central opening 21 through which the arm 18 may be manipulated to adjust the anvil to either a permanent or temporary stapling position. The rear portion of the member 15 may be hollowed out or in any other manner cut or formed to permit movement of the head 12 to the position shown by the broken lines of Fig. 1, in which case the device is used as a tacker. In the embodiment illustrated, a portion of the rim of the member 15 is cut away, as at 15', to permit such swinging while the bottom face of the member 15 is provided with the opening 21'.

The head 12 is provided with a housing 21 which is of novel and unusual construction. It will be noted that said housing 21 is formed entirely of one piece. In the formation of said housing a blank, as shown in Fig. 4, is punched out of sheet metal in generally triangular shape. Said blank has a portion thereof removed as at 22, thereby bifurcating an apex of the triangle into two ears 23. A cut is made across the base of the removed portion 22 as shown at 24 to aid in the formation of the housing. At the side

5 opposite to the bifurcated apex a pair of flaps 25 are formed and the remaining sides of the triangular blank are curved as shown at 26. The portion 27 is cut back further than the line z along which the flaps 25 are adapted to be folded.

In the formation of the housing out of the blank shown in Fig. 4 three zones are defined in said blank extending between the bifurcated apex and the side opposite thereto by lines x, x, y, y. The central of said zones between lines x, x, is adapted to form the base portion 28 of a channel formation and the outer two zones between lines x—y and lines x—y, are adapted to form the leg portions 29 of said channel formation. Said channel formation is struck into the blank as for example by upsetting the portion 28.

Prior to the upsetting of said portion 28, it is preferable that the flap portions 25 be bent perpendicularly to the wings 30 along the line z—z in a direction which will result in said flaps 25 joining one another in the formation of a front wall 31 for said housing, and to serve as spacing means for spacing said wings 30 apart. Since the lines z—z are offset from the end 27 20 of the channel forming zones, upon completion 25 of the housing there will be a space between the front wall 31 formed by the ears 25 and the end 27 of the channel formation through which a staple will be ejectable.

In upsetting said zone x—x, and thereby forming the arms 29 of the channel portion defined by the zones x—y, x—y, the flaps or wings 30 are folded parallel to and upon said portions 29, leaving, however, sufficient space between the outer face of the arm portions 29 and the inner face of said wings 30 to accommodate the thickness of the staples S intended to be used with our stapling device.

It will be seen that the resulting housing consists of a substantially right angle triangular member with its bottom wall depressed inwardly and upwardly by reason of the channel formation, its arcuate top open, and its walls or wings 30 spaced from one another by reason of the front wall as formed by the flaps 25. A staple ejecting opening is formed at the front lower portion of the housing by reason of the offset portion 27 and said opening is designated by the character 32 in the drawings. Rows of staples 40 which are inserted into the rear of the housing (the righthand side as viewed in Figs. 1, 2 and 3) will be slideable upon the channel formation with the bases of said staples riding upon the portion 28 and the arms of said staples depending into the space formed between the portions 29 of said channel formation and the inner walls of the wings 30. The portion 27 is cut back sufficiently so that the space 32 resulting between the forward end of the formation and the inner face of the wall 31 is sufficient to permit passage of one staple at a time.

An auxiliary member 33 of generally U-shaped cross-sectional formation is provided between the ears 23 for strengthening that portion of the housing and for providing rigid spacing means permitting the attachment of the pin 13 to the staple driving head 12. A strong leaf spring 60 is riveted to the inner bottom of the member 33 at 61 and bears against the upper surface of the base 10, thereby maintaining the head 12 resiliently spaced above the base 10 and causing same to return to said position upon release thereof after having been depressed in an operating stroke. A portion of the leaf spring 60

extends upward as shown at 34, and has a hooked portion for a purpose to be described.

It is to be noted that the ears 23 are not deformed while the channel portion is struck upward. Hence the ears remain as extensions of the wings 30 and are disposed parallel to one another as shown, Figs. 1, 2 and 5. These ears are welded or otherwise fixed between the arms of the U-shaped member 33.

In order to force the staples forward towards the wall 31, we have provided a member 35 of the same general cross-sectional size as a staple. Said member is provided forwardly thereof with an upwardly struck portion 36 to engage the end of a row of staples. In the upper wall of said member 35 we attach an angle-shaped member 37 through an opening 38 of which a staple plunger rod 39 passes. Said staple plunger rod has a hooked portion 40 at the forward end thereof and a triangular key portion 41 formed at the rearward end thereof with a depending hook 42 provided thereon. Said hook 42 is adapted to extend into a slot 43 formed in the upper surface of the wall 28 of the channel formation so that when the spring 44 which is disposed upon said plunger rod 39 is compressed upon insertion of a row of staples into the staple magazine, the plunger rod 39 will be held in position, as shown clearly in Fig. 5. The hooked portion 40 is provided to prevent the plunger from sliding out of the member 37 through opening 38, and to aid in maintaining the entire mechanism consisting of plunger 39, spring 44 and member 35 as an easily manipulable unit.

We have provided a cover member 45 of generally channel-shaped cross section, and which is pivoted to the upper front portion of the housing 21 at 46. Said cover member 45 completely encloses the housing along the open side 26 when in a closed position. The cover member may be engageable by the housing wings 30 by friction means or some other well known expedient such as for example cooperating depressions 47.

It will be noted that when the cover member is moved to a closed position, as shown in Fig. 2, its bottom surface will engage against the key 41 forcing the plunger 39 slightly forward, thereby increasing the compression of the spring 44. When finally in closed position, the cover member serves to conceal the entire staple magazine and plunger mechanism. The cover member is provided with a downwardly struck detent 47' which engages the hooked extension 34 of the spring 44 when the cover is in closed position and aids in maintaining said closed position. A finger portion 45' is provided on said cover member to aid in opening same.

It will be noted that the magazine is formed in a simple and novel manner and that no parts are necessary to confine the staples other than an L-shaped member having one arm 48 disposed slightly above the portion 28 to prevent staples from moving upwards. Each of the inner walls of the wings 30 is provided with one of such L-shaped members so that an arm 48 is disposed on either side of the row of staples. The other arms 49 of the L-shaped member are disposed slightly rearward of the front wall 31 and define thereby a passageway between the front wall and themselves within which the driving plunger may ride. Said members may be attached within the housing by any well known means, such as for example, rivets 50.

The staple driving plunger of our new device is a novel and simple mechanism and is best de-

scribed with reference to Fig. 8. The entire plunger mechanism consists of a flat blade 51, which we prefer making of spring steel, attached to a depressing member 52, whereby a person 5 may downwardly urge the depressing member 52 and move the blade 51 down into the driving plunger guide passageway defined between the arms 49 and the front wall 31 to eject a staple from the row of staples in the staple magazine 10 disposed along the member 28, and forced against the front wall of the housing, by the spring 44. A continuation 51' of the blade 51 is bent at right angles thereto to provide for attachment to the member 52 by the rivet 53 and still a further extension of the portion 51' provides a downwardly depending hook portion 54. In order to strengthen and stiffen the entire assembly an L-shaped member 55 is riveted to the blade 51 at 56 and attached thereto by means of the common rivet 20 53 at the depressing member 52.

The cover member 45 is provided forwardly thereof with an opening 57 through which the upper portions of the arms 49 extend. Said upper portions of the arm 49 are designated by the 25 reference character 58 and same serve as stops limiting downward movement of the staple driving plunger. The upward movement of the staple driving plunger is limited by the hook of the member 54 engaging the underside of the cover member 45 as shown in Fig. 2. A leaf spring 59 is attached to the bottom of the cover member 45 at 59' and said leaf spring engages against the bottom of the hook member 54, thereby normally causing same to move upward. This, of course, 30 holds, the hook portion against the underside of the member 45 as explained above.

Thus it will be seen that the staple driving plunger may be operated in a simple and efficient manner and that it may be removed from the device as for example for storing or inspection or replacement by merely bending member 54 to the left as shown in Fig. 2, and removing the entire assembly.

Presuming that the stapling device is empty, 45 the member 35 is at its extreme left disposed upon the channel-portion 28 and the cover member is closed. The hooked portion 42 is at the extreme left of the slot 43 as shown in Fig. 2. It is desired to load the stapling device so that it may be further operated. First, the cover member 45 is grasped by the finger portion 45' and swung upwardly about its pivot point 46 and opened as shown in Fig. 5, thereby permitting the key portion 41 of the plunger 39 to move to its extreme right in the slot 43. This movement has also disengaged the hook portion 34 from the detent 47'. The key is then removed from the slot 43 manually and the entire plunger spring 44, member 35, and the plunger 39, are 50 pulled out of the staple magazine. A row of staples is then inserted upon the portion 28 and pushed into the magazine, following which the member 35 is again inserted into the magazine and pushed forward until the portion 36 engages the row of staples S. The key 41 is then further pushed forward compressing the spring 44 and is hooked into the slot 43 by means of the downwardly depending hook 42. Following this, the cover member 45 is moved downward 55 and snapped into position, thereby causing the key member to move a slight amount to the left, further compressing the spring 44.

Presuming that two or more sheets of paper are disposed upon the anvil preparatory to stapling them, the depressing member 52 is struck 70

by the operator and moved downward causing the blade member 51 to pass between the front edges of the arms 49 and the inner face of the front wall 25. The bottom of the blade 51 engages the frontmost staple of the row S and forces it out through the opening 32. The staple is guided out of the housing and is completely confined on all sides during this time at its top by the blade bottom 51; at its rear by the remainder of the staple row being forced forward 10 by the spring 44; and at its front by the wall 25, thereby preventing buckling, jamming or clogging of the mechanism.

As the staple is being pushed downward by the blade 51 so that its legs pass through the paper to enter the appropriate depressions in the anvil for being bent to finally deformed position on the other side of the paper, the row of staples in the meantime is constantly being forced towards the wall 25, but cannot reach same because of the fact that the blade member has now taken the position of the first staple. During this downward movement, the lower portion of the member 54 has flexed the leaf spring 59 downward so that after the deformation of the staple has occurred and the depressing member 52 is released, the leaf spring 59 forces the entire staple driving plunger upward until the hook portion of the member 54 engages the bottom of the cover member 45 as shown in Fig. 2. As the blade 30 passes upward, past the row of staples, thereby leaving a space where the former staple was, the next staple in line is pushed into position by the spring 44 and the stapling device is poised for another stroke of the staple driving plunger.

It will be seen that we have provided a novel and exceedingly efficient mechanism in connection with our novel construction. As a whole, it is to be noted that the stapling device we have presented is ideally suited for low cost manufacture in large quantities and that despite its obviously economical features, it is mechanically efficient and will discharge its duties in an expeditious manner.

It is believed that our invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of our invention as defined in the appended claims.

What we claim and desire to secure by Letters 55 Patent of the United States is:

1. In a stapling device, including a housing and means for maintaining a row of staples within said housing positioned for ejection therefrom, means for consecutively ejecting said staples from said housing comprising a substantially flat reciprocable blade, means associated with said housing guiding and confining the edges of said blade during its operation, and means for actuating said blade, said guiding means including a wall of said housing upon which said flat blade is adapted to ride and means for holding said blade slidably against said wall, said magazine being of substantially inverted U-shaped cross-section and being integrally formed from 70 the housing, the side walls thereof being spaced from the inner faces of said housing to provide a space within said housing and upon which a row of staples may ride and be maintained.

2. A stapling device, comprising a base, a hous-

ing pivotally mounted thereon, a channel-shaped staple support formed as the bottom wall of said housing, upstanding side walls on said housing, a front wall, and a pivotally mounted top wall, a plunger reciprocably mounted on said front wall, L-shaped members attached to said upstanding side walls, one arm of each of said L-shaped members being spaced from said front wall thereby defining guides within which said plunger blade is adapted to ride, and be received, an arm of each of said L-shaped members being spaced from said channel-shaped support thereby confining staples disposed thereon, means for operating said plunger, spring means forcing said staples into the path of said plunger blade and an opening through which said staples are adapted to be ejected.

3. In a device of the character described, a base, a housing pivotally mounted on said base, a staple magazine in said housing, means associated with the magazine for moving the staples to ejectable position, reciprocable means in said housing for ejecting staples from said magazine consecutively and driving same into the work, said housing having one side thereof open to permit access to said magazine, said side being provided with a cover member pivoted to said housing and adapted to enclose said housing and conceal the interior thereof, said cover member having means associated therewith for normally urging said reciprocable means in a non-ejecting direction.

4. In a device of the character described, a base, a housing pivotally mounted on said base, a staple magazine in said housing, means associated with the magazine for moving the staples to ejectable position, reciprocable means in said housing for ejecting staples from said magazine consecutively and driving same into the work, said housing having one side thereof open to permit access to said magazine, said side being provided with a cover member pivoted to said housing and adapted to enclose said housing and conceal the interior thereof, said cover member having means associated therewith for normally urging said reciprocable means in a non-ejecting direction, said cover member serving to limit movement in said last mentioned direction.

5. In a device of the character described, a base, a housing pivotally mounted on said base, a staple magazine in said housing, reciprocable means in said housing for ejecting staples from said magazine consecutively, said housing having one side thereof open to permit access to said magazine, said side being provided with a cover member pivoted to said housing and adapted to enclose said housing and conceal the mechanism thereof, said magazine being provided with spring means for urging said staples to ejectable position, said cover being adapted to aid in compressing said spring means when in closed position.

6. In a device of the character described, a base, a housing pivotally mounted on said base, a staple magazine in said housing, reciprocable means in said housing for ejecting staples from said magazine consecutively, said housing having one side thereof open to permit access to said magazine, said side being provided with a cover member pivoted to said housing and adapted to enclose said housing and conceal the mechanism thereof, spring means normally maintaining said housing spaced from said base, said spring means being secured to said housing intermediate the ends thereof, one end of said spring engaging

said base and the other end of said spring being formed with a hooked portion for engaging a portion of said cover to releasably maintain same in a closed position.

7. In a device of the character described, a housing, a staple magazine in said housing, an opening in said housing through which staples may be consecutively ejected, a plunger device, means associated with the said staple magazine urging said staples into the path of said plunger whereby same are poised for consecutive ejection, said means comprising a rider riding said magazine, an elongated member associated with said rider for the manipulation thereof, and a compressible spring disposed upon said elongated members adapted to force said rider against said row of staples, said magazine having means whereby said elongated member may be removably engaged thereto while said spring is under compression, including a slot, said elongated member being provided with means engaging said slot, said housing being open at one end, a cover for closing the same, said cover engaging an end of said elongated member when in closed position serving to thereby add compression to the already compressed spring.

8. In a device of the character described, a housing, a staple magazine, a plunger for ejecting staples from said magazine, an opening in the housing through which said plunger extends, said plunger comprising a hand depressing portion for actuating same, a staple driving blade attached to said depressing portion, and resilient means also attached to said depressing portion removably engaging the housing at the edge of said opening to maintain the plunger in assembled position on said housing.

9. In a device of the character described, a housing, a staple magazine, a plunger for ejecting staples from said magazine, an opening in the housing through which said plunger extends, said plunger comprising a hand depressing portion for actuating same, a staple driving blade attached to said depressing portion, and resilient means also attached to said depressing portion removably engaging the housing at the edge of said opening to maintain the plunger in assembled position on said housing, said last mentioned means permitting the complete removal of the plunger from the housing upon the application of pressure disengaging same from said edge of the opening.

10. In a device of the character described, a housing, a staple magazine, a plunger for eject-

ing staples from said magazine, an opening in the housing through which said plunger extends, said plunger comprising a hand depressing portion for actuating same, a staple driving blade attached to said depressing portion, and resilient means also attached to said depressing portion removably engaging the housing at the edge of said opening to maintain the plunger in assembled position on said housing, said last mentioned means also acting as stop means to limit upward movement of said plunger when in operative assembled position on said housing.

11. In a stapling device, an enclosed housing formed from a single sheet of material and adapted to have a row of staples maintained therein for consecutive ejection therefrom, means for consecutively ejecting said staples from said housing comprising a substantially flat reciprocable blade, means associated with said housing guiding and confining the edges of the blade during its operations, and means for actuating the blade, said guiding means including a vertically arranged wall of said housing upon which said flat blade is adapted to ride and means spaced from said wall to permit the sliding motion of said blade, a channel formation formed integral with said housing and being a wall thereof horizontally arranged and substantially perpendicular to said first mentioned wall, said formation being adapted to guide and maintain a row of staples thereon, said channel formation terminating short of the first mentioned wall and having resilient means associated therewith for forcing a row of staples positioned thereon against said first mentioned wall and into the path of the blade.

12. In a device of the character described, a one piece sheet metal housing including wing-like side walls, a vertically arranged end wall, and a bottom wall, said bottom wall being of inverted U-shaped cross-section and having an end thereof terminating short of the vertically arranged end wall, said bottom wall being adapted to have a row of staples slidably positioned thereon, means associated with said bottom wall normally urging said row of staples towards the end wall and into engagement therewith, and staple driving means associated with said end wall and movable parallel thereto and into the space between the end of the bottom wall and said end wall whereby a staple positioned within said space will be driven out of the housing.

CHARLES I. TAGER
HANS C. STOCKEL.
